UNITED STATES PATENT OFFICE.

AUGUST J. GUSTAFSON, OF CHICAGO, ILLINOIS.

APPARATUS FOR RAISING SUNKEN VESSELS.

1,281,949.

Specification of Letters Patent.

Patented Oct. 15, 1918.

Application filed May 16, 1918. Serial No. 234,971.

To all whom it may concern:

Be it known that I, AUGUST J. GUSTAFSON, a citizen of the United States, residing at Chicago, in the county of Cook, and in the State of Illinois, have invented certain new and useful Improvements in Apparatus for Raising Sunken Vessels, of which the following is a specification.

This invention relates to improvements in apparatus for raising sunken vessels, and one of the objects of the invention is to provide an improved apparatus of this character which is adapted to being floated upon the water to a position over the sunken vessel, to be submerged or sunk so as to stand astride of the vessel, in which latter position parts of the apparatus are then adjusted so as to grip the vessel and to raise the latter by the rising movement or buoyant action of the apparatus itself. A further object is to provide an improved apparatus of this character embodying a series of hollow, fluid-tight compartments or elements closed to each other and adapted to be filled with water to cause the apparatus to sink or submerge, and having means for exhausting the water from one or more of the compartments to cause the elements to automatically assume a position with respect to the supporting structure so that it will be in a position to grip the vessel, while one or more other compartments remain full of water to maintain the elements submerged. After the elements have assumed a proper position with respect to each other and to the vessel, the water is exhausted or removed from the other compartments of the elements so that the apparatus will become buoyant, and by means of which buoyancy the apparatus will rise to the surface of the water, carrying with it the sunken vessel which it grips, and which vessel will be gripped or held in the apparatus between the said elements.

A further object is to provide an improved apparatus of this character having means whereby the ingress and egress of the water into and out of the buoyant elements may be controlled at will.

To the attainment of these ends and the accomplishment of other new and useful objects as will appear, the invention consists in the features of novelty in substantially the construction, combination and arrangement of the several parts, hereinafter

more fully described and claimed and shown in the accompanying drawings, in which:

Figure 1 is a view partly in side elevation and partly in vertical section of an improved apparatus of this character and constructed in accordance with the principles of this invention and showing the apparatus as floating upon the water.

Fig. 2 is an enlarged detail view of one form of the apparatus by means of which the ingress and egress of the water from the buoyant elements may be controlled.

Fig. 3 is an enlarged detail view partly in elevation and partly in section of a portion of one of the buoyant elements.

Fig. 4 is a view similar to Fig. 1 showing the apparatus sunken and with the elements in position to grip the vessel therebetween.

Fig. 5 is a side elevation of Fig. 1.

Fig. 6 is an enlarged detail perspective view of a portion of the apparatus.

This apparatus consists essentially of a supporting structure which may be of any desired size, configuration, and construction suitable for the apparatus but comprises a main support 10, preferably of angle-iron construction, suitably braced and may be in the form of a tower at the base of which is arranged a structure comprising the members 11-12, which may also be of any desired construction but is preferably formed of angle-iron suitably braced. These members 11-12 are pivotally connected as at 13-14 with the supporting tower 10, so as to move freely about the pivots, and the proximate ends of the members 11-12 are themselves pivotally connected as at 15, so that the ends of the members 11-12 will be held against separation as the members are moved about their pivots 13-14. Connected with each of the members 11-12, preferably adjacent the free ends 16-17 thereof are a plurality of fluid and air-tight elements 18, arranged on both sides of the pivot 15 of the members 11-12, and as the construction and operation of each of these elements 18 is the same, a specific description of one will apply equally as well to them all.

The element 18 is pivotally connected in any suitable manner such as by means of a hinge 19 with the end of the respective members 11-12, and these elements 18 may be of any desired size and configuration but

are preferably angular in cross-section so as to present a substantially flat surface 20 to the vessel, and the bottom of the elements is preferably arranged on an incline or bevel 5 21, so as not to interfere with the free movement of the element 18 about its pivot, when the apparatus is submerged, and which face 21 will move over the bottom of the body of water.

10 The element 18 is provided with a partition 22, dividing the same into two compartments 23-24, and the partition 22 is preferably inclined so that the compartment 23 will have a greater area at its base for 15 a purpose to be set forth.

The compartment 23 is provided with an opening 25, preferably located in the base of the compartment and the compartment 24 is also provided with an opening 26 preferably in its base, both for a purpose to be 20 hereinafter set forth.

If desired, the members 11-12 may be provided at their outer extremities, 16-17, with depending portions 27 between which 25 the elements 18 are adapted to operate, and these depending portions 27 serve as guides to hold the elements 18 in position.

A pipe 28 is provided and has communication with the compartment 23, and this pipe 30 has communication with a pipe 29, the latter being supported by the member 11 or 12 and has a suitable jointed connection with the pipe 28 so as not to interfere with the movement of the element about its pivot 19. 35 Obviously this jointed connection may be made in any desired or well-known manner, and may be in the pivot itself, if desired.

Connected with the pipe 29 is another pipe section 30 and these two sections 29-30 40 also have a jointed communication so as not to interfere with the pivotal movement of the member 11 with respect to the tower 10. The pipe section 30 extends for any desired distance above the members 11-12, preferably 45 to the supporting platform 31 mounted upon the tower 10 at any desired elevation. Upon this platform 31 is arranged suitable mechanism for controlling the passage of air through the pipes 30-29 and 50 into and out of the compartment 23. In the present form of the invention this mechanism is illustrated as embodying an air pump 32 with which the pipe 30 has communication. This pump may be actuated 55 by means of a boiler 33 through the pipe communication 34. In order to control at will the flow of air through the pipe 30, so that air may be directed into the compartment 23 and removed therefrom, when

60 desired, any suitable mechanism may be provided such, for instance, as a two-way valve 35 of an ordinary and well-known construction, which, when the valve is in one position will form communication between the 65 air pump 32 and the pipe 30 so that air

from the pump being forced through the pipe 30 will flow through the pipe section 29, pipe 28, and into the compartment 23. The pressure of the air thus forced into the compartment 23, will operate to force the water 70 which is in the compartment, out of said compartment through the outlet 25. When the two-way valve 35 is in its other position the pump 32 will be cut off from communication with the pipe 30, and communication 75 between the pipe 30 and the atmosphere will be established, so that the pressure of the air in the compartment 23 will be relieved, and the water, rushing into the compartment 23 through the opening 25, will force the air out of the compartment 23, thereby allowing the compartment to be filled with water.

A similar communication is established between the compartment 24 and the pump 85 32, preferably through the medium of a pipe 36 which has communication with the compartment 24 and with a pipe 37, the latter having communication with a pipe section 38, which, in turn, communicates with the pump 32 in a manner similar to pipe 30. A two-way valve may be also provided in the pipe section 38 for controlling the ingress and egress of the water into and out of the compartment 24 through the opening 26.

Thus, it will be manifest that the flow of the water into and out of the respective compartments 23-24, which latter are out of communication with each other, is at all 100 times under the absolute control of the operator.

It is thought that the operation of this portion of the mechanism will be clearly understood from the above description, but, 105 briefly stated, it is as follows:

The members 11-12 may be adjusted with respect to each other about their pivots 13-14, and also about the pivot 15 to space the elements 18 according to the width of 110 the vessel or article to be raised, it, of course, being understood that the water is forced from the compartments 23-24 of the elements 18 so that they will be buoyant and the whole structure will float upon the water. 115 The openings 25-26 are so located with respect to the compartments that the openings will be at all times submerged, and if desired, any suitable or well-known valves may be applied to these openings, although 120 the use of valves is not necessary.

The adjustment of the members 11-12 with respect to each other, may be accomplished in any suitable manner such, for instance, as a cable 39, one end of which 125 may be connected as at 40 with the member 11 and the cable may be passed over a suitable pulley 41 to a windlass 42, the latter being arranged on a suitable shaft 43 supported upon the platform 31, so that by 130

operating the windlass the two members 11-12 may be swung about their pivots 13-14, to cause the outer ends 16-17 to move toward each other, and when the windlass is released, the members 11-12 will move in opposite directions about their pivots.

Any number of the elements 18 may be employed on each side of the apparatus, and 10 when the apparatus has been floated to a position above the vessel to be raised which may be ascertained by sounding or in any other manner, it being, of course, understood that the compartments 23-24 of the elements 18 are filled with air, the water being exhausted therefrom. In this position, the two-way valves 35 are opened so as to establish communication between the compartments 23 of the elements 18 and the atmosphere. The air in these compartments will then be forced therefrom and the water will 20 flow thereto through the openings 25. At the same time the two-way valves controlling the air in compartment 24 is positioned to exhaust the air therefrom by the inflow of the water into the compartment 24 through the opening 26. When these elements 18 are thus filled with water it will be manifest that the loss of buoyancy will cause the apparatus 25 to submerge or sink from the position shown in Fig. 1 to the position shown in Fig. 4. In this sunken position the elements 18 will stand astride of the vessel 44. The next operation is the adjustment of the two-way valve 35 so as to cut off communication between the compartment 23 and the atmosphere, and to reestablish communication between the compartment 23 and the pump 32. The pump 32 is then operated to force the 30 air through the pipes 30, 29, 28 and into the compartment 23. As the air enters the compartment the pressure thereof will force the water out of the compartment 23 through opening 25. The elements 18 will then become partially buoyant with the result that they will automatically swing about their pivots 19 from the position shown in Fig. 1 to that shown in Fig. 4. When the elements 18 have thus been positioned, and in order 35 to maintain them so adjusted so that the weight of the article being lifted by them will not cause the elements to swing about their pivots in the opposite direction and thereby drop or release the article, any suitable mechanism may be provided. A simple and efficient means comprises a cable 45, the ends of which are secured as at 46^A to the elements 18 and the cable passed over a suitable windlass or drum, similar to windlass 0 or drums 42, on the shaft 43 and which windlass or drum when operated tends to actuate the cables 45 and thereby move the elements 18 about their pivots in one direction and hold them in such adjusted positions. Obviously, the direction of movement of the ele-

ments 10 by the cables 45 will be controlled by the direction of operation of the windlasses or drums 42.

Obviously the shaft 43 may be operated in any desired or suitable manner, and the windlass or drum 42 may be provided with suitable well-known clutch devices whereby they may be independently controlled.

With the parts thus adjusted, and when it is desired to elevate the apparatus and the sunken vessel, it is only necessary to adjust the two-way valves which control the flow of air into and out of the compartment 24 of the elements 18. And by establishing communication between the compartment 24 and the pump 32, it will be manifest that by forcing the air into the compartment 24, the water therein will be forced out of the opening 26, with the result that the elements 18 will become buoyant, and the apparatus will then rise, carrying with it the vessel 44. Obviously, as before stated, the openings 25-26 are in such positions that they will be always maintained closed by the water upon which the apparatus floats.

If desired, the shape of the points or edges 47 of the elements 18 may be such as to form claws or fingers which will insure a firm grip upon the vessel 44.

Obviously suitable stop devices 48 may be provided for limiting the movement of the elements 18 about its pivot in one direction.

Obviously many changes in the details of construction, and in the combination arrangement of the several parts may be made, within the scope of the claims, without departing from the spirit of this invention, and it is also obvious that flexible joints may be provided where necessary and suitable pulleys may also be provided for the various cables at the necessary points.

What is claimed as new is:

1. An apparatus of the character described, embodying a floating structure, said structure embodying opposed hollow and fluid tight elements each having separate compartments, means for filling said compartments with water to sink the said structure, means for adjusting the said elements with respect to the structure and to each other to cause the elements to approach each other, and means whereby the water may be exhausted from the said elements to cause the latter to be buoyant to raise the structure.

2. An apparatus of the character described, embodying a floating structure, said structure embodying opposed hollow and fluid tight elements, means controlled at will for filling said elements with water to sink the structure, means controlled at will for removing a portion of the water from the elements, means whereby the removal of such portion of the water from the elements will cause the latter to be moved toward each other and while submerged, and means for

removing an additional quantity of the water from the elements.

3. An apparatus of the character described, embodying a floating structure, said structure embodying opposed and spaced fluid tight elements, said elements each embodying two compartments therein separate from each other, means for filling both of the compartments with water to sink the said structure, means for removing the water from one of the compartments whereby the elements will automatically adjust themselves with relation to the supporting structure, and means for removing the water from the other compartment of the elements whereby said structure will become buoyant.

4. An apparatus of the character described, embodying a floating structure, said structure embodying opposed and spaced fluid tight elements, said elements each embodying two compartments therein separate from each other, means for filling both of the compartments with water to sink the said structure, means for removing the water from one of the compartments whereby the elements will automatically adjust themselves with relation to the supporting structure, means for removing the water from the other compartment of the elements whereby said structure will become buoyant, and means whereby the ingress and egress of the water into and out of the said compartments may be controlled at will.

5. A floating apparatus of the character described, embodying a supporting structure, a plurality of hollow opposed and spaced elements pivotally connected with the structure and for adjustment with respect thereto, means whereby said elements may be filled with water to sink them, means for removing a portion of the water from the elements to cause them to automatically swing about their pivots, into operative positions with respect to each other and while they are submerged, and means for removing additional quantities of water from the said elements to cause them to become buoyant.

6. A floating apparatus of the character described embodying a supporting structure, a plurality of opposed and spaced hollow fluid tight elements shiftably mounted upon the said structure, said elements each having a plurality of compartments therein separate from each other, means whereby said compartments may be filled with water to sink them, means for removing the water from one of the compartments to cause the elements to become partially buoyant so as to automatically shift themselves with respect to the supporting structure and while the elements are submerged and means for removing the water from another compartment to cause the element to become more buoyant.

7. A floating apparatus of the character described embodying a supporting structure, a plurality of opposed and spaced hollow fluid tight elements shiftably mounted upon the said structure, said elements each having a plurality of compartments therein separate from each other, means whereby said compartments may be filled with water to sink them, means for removing the water from one of the compartments to cause the elements to become partially buoyant so as to automatically shift themselves with respect to the supporting structure, and while the elements are submerged, means for removing the water from another compartment to cause the element to become more buoyant, and means whereby the said structure may be adjusted to vary at will the initial distance between opposed elements.

8. A floating apparatus of the character described embodying a supporting structure, a plurality of opposed and spaced hollow fluid tight elements shiftably mounted upon the said structure, said elements each having a plurality of compartments therein separate from each other, means whereby said compartments may be filled with water to sink them, means for removing the water from one of the compartments to cause the elements to become partially buoyant so as to automatically shift themselves with respect to the supporting structure, and while the elements are submerged, means for removing the water from another compartment to cause the element to become more buoyant, and means for bodily shifting opposed elements with relation to each other to vary at will the extent of the space between the said opposed elements.

9. A floating apparatus of the character described, embodying a supporting structure, spaced opposed hollow fluid tight elements mounted upon the structure for adjustment toward each other, means for filling said elements with water to sink them and the said structure, provisions whereby the elements may be rendered partially buoyant to cause them to be thereby shifted toward each other and while submerged, and provisions whereby the elements may be rendered more buoyant after being thus adjusted, whereby said elements and the structure will rise in the water.

10. A floating apparatus of the character described, embodying a supporting structure, spaced opposed hollow fluid tight elements mounted upon the structure for adjustment with respect thereto and toward each other, means for filling said elements with water to sink them and the said structure, provisions whereby the elements may be rendered partially buoyant to cause them to be thereby shifted toward each other and while submerged, provisions whereby the elements may be rendered more buoyant after

being thus adjusted, whereby the said elements and the structure will rise in the water, and additional means for maintaining the said elements in their adjusted position 5 toward each other.

11. A floating apparatus of the character described, embodying a supporting structure, spaced opposed hollow fluid tight elements mounted upon the structure for adjustment with respect thereto and toward each other, means for filling said elements with water to sink them and the said structure, provisions whereby the elements may be rendered partially buoyant to cause them 10 to be thereby shifted toward each other and while submerged, provisions whereby the elements may be rendered more buoyant after being thus adjusted whereby said elements and the structure will rise in the water, and 15 positive means for maintaining the said elements against separation after the said shifting thereof.
12. An apparatus of the character described, embodying a supporting structure, 20 a hollow fluid tight lifting element connected with the structure for adjustment with respect thereto, means for filling the said element with water to sink the same, provisions whereby a portion of the water may 25 be removed from the element when submerged to cause the element to be shifted with respect to the supporting structure and into operative position, and provisions whereby an additional quantity of water 30 may be removed from the element to cause 35 said element to become more buoyant to float in the structure.
13. An apparatus of the character described, embodying a supporting structure, 40 a hollow fluid tight lifting element connect-

ed with the structure for adjustment with respect thereto, said element embodying two compartments separated from each other, means for filling the compartments with water to sink the element and the said supporting structure, provisions for removing the water from one of the compartments to cause the element to become partially buoyant and thereby automatically shift itself with respect to the supporting structure and 45 while submerged, and provisions for removing the water from the other compartment to render the element more buoyant to float the same and the said supporting structure.

14. An apparatus of the character described, embodying a supporting structure, a hollow fluid tight lifting element connected with the structure for adjustment with respect thereto, said element embodying two compartments separate from each other, filling the compartments with water to sink the element and the said supporting structure, provisions for removing the water from one of the compartments to cause the element to become partially buoyant and thereby automatically shift itself with respect to the supporting structure and while submerged, provisions for removing the water from the other compartment to render the element 50 more buoyant to float the same and the said supporting structure, and means under the control of the operator for maintaining the said element in its adjusted or shifted position with relation to the said supporting structure.

In testimony whereof I have signed my name to this specification on this 14th day of May, A. D. 1918.

AUGUST J. GUSTAFSON.
